INTERNAL COMBUSTION HAMMER

Clifford E. Fitch, Cleveland, Ohio, assignor to
 Chicago Pneumatic Tool Company, New York,
 N. Y., a corporation of New Jersey

Application August 11, 1939, Serial No. 289,547

1 Claim. (Cl. 123—7)

This invention relates generally to percussive tools, for example, tie tampers, and more particularly to a percussive tool embodying, in combination, either a single or double acting internal combustion engine and a free piston type of hammer assembly.

A hammer assembly of the free piston type generally comprises a reciprocable cylindrical cage so constructed as to provide a cushioning means at one or both ends thereof, and a hammer piston positioned within the cage and adapted to be driven by air or spring pressure, generated by relative movement of the cage, to deliver a blow upon a working implement such as a drill steel or tamping bar. Hammer assemblies of this type have been used heretofore chiefly in electrically operated tools, and it is thought that the present invention, in one of its broad aspects, resides in the combination of an internal combustion engine with a hammer assembly of the type described.

The invention has a particular reference to the use of a free hammer piston with a two-cycle internal combustion engine of the double acting type; namely, one that has a single driving piston and an explosion or combustion chamber adjacent each end of the driving piston. A double acting engine has many advantages over the single acting type, but the principal advantage is gained by the elimination of the usual spring for returning the driving piston through its compression stroke. This spring requires frequent replacement due to breakage and, moreover, reduces the efficiency and power of the engine by absorbing energy when compressed during the power stroke of the piston.

While the advantages of the double acting engine over the single acting type are apparent, they have been attained only upon the solution of newly created problems. In the single acting type of internal combustion hammer, the piston usually delivers a direct blow either to the working implement or to an anvil block abutting the implement with non-yielding engagement. In such an arrangement, the length of stroke of the piston is not uniform due to the fact that the position of the working implement at the time of impact is not always the same. The return spring permits such variations in length of stroke. On the other hand, the use, in a double acting engine, of ignited gas to return the piston, in place of the spring that characterizes the single acting type, necessitates a substantially uniform length of piston stroke, since the explosion in the lower chamber must be timed to occur at a fixed point in the operation of the machine. A double acting engine with a uniform piston stroke will not produce the best results if the piston is required to strike the implement directly, because if timing mechanism is regulated for a short stroke the force of blow is frequently too weak,

whereas, the selection of a relatively long stroke might result in stalling the engine whenever the position of the working implement happened to be unusually high. According to the present invention, this defect is remedied by the use of a free piston hammer assembly, wherein the cylindrical cage is directly connected to the driving or engine piston of uniform stroke and the hammer piston moves through a variable range of movement, within the cage, to strike the working implement.

One object of the invention is to increase the efficiency and adaptability of a percussive tool by associating, in combination, an internal combustion engine and a free piston type hammer assembly.

Another object of the invention is to produce a practical double acting internal combustion driven tool by imparting percussive blows from a driving piston to a working implement through an intermediate hammer assembly which includes a hammer piston having a variable range of movement.

Other objects and structural details of the invention will be apparent from the following description when read in conjunction with the accompanying drawings wherein:

Fig. 1 is a longitudinal section through a tie temper embodying the mechanism of the invention, the driving piston being in its uppermost position, certain of the ignition apparatus being shown schematically;

Fig. 2 is an enlarged view of the upper section of Fig. 1;

Fig. 3 is a view similar to Fig. 2, showing the driving piston in descending position;

Fig. 4 is an enlarged view of the lower section of the tool, showing the hammer assembly in descending position;

Fig. 5 is a view similar to Figs. 2 and 3, showing the driving piston at the end of its descending stroke;

Fig. 6 is a view similar to Fig. 4, but showing the hammer assembly at the time that the driving piston is at the end of its descending stroke; and

Fig. 7 is an enlarged detail view of the lower end of the starting plunger, taken along the line 1—1 of Fig. 2.

For purposes of description the tool may be considered as consisting of two cooperating sections which form the opposite, or upper and lower, ends of the tool. The upper end of the tool is constructed as an internal combustion engine and the lower end as a support and guide for the impact delivering elements. As shown in Fig. 1, the chief supporting elements of the tool are a pair of cylinders 8 and 9, at the upper end, and a downwardly extending barrel 10, at the lower end. Movable within the cylinders 8 and

9 is a driving piston 11 formed with a connection rod 12 which extends downward into the barrel 10 and rigidly connects the piston to a cylindrical cage 13 positioned within the barrel and movable relatively thereto. Mounted for relative movement inside the cylindrical cage 13 is a hammer piston 14 which is caused, by air compression, to deliver a blow upon the upper end of a working implement 15 which, in the present instance, is a tamping bar.

The shank of the bar 15 is enclosed by the lower end of the barrel 10 and by an extension 16 secured to the barrel by bolts 17. A bushing 18 for the bar 15 is supported inside the extension 16 at its lower end. In order to limit the downward movement of the tamping bar and to lessen the shock of the impact delivered thereon, a cushioning assembly is positioned atop the bushing 18. This assembly comprises a cushion 19 made of rubber or similar material, a retaining ring 21 and a contact disc 22 which rests on the upper end of the cushion in position to be engaged by the lower surface of a shoulder 23 formed on the bar 15. To limit the movement of the bar in the opposite, or upward, direction, a spacing ring 24 is placed within the barrel 10 above the shoulder 23.

Considering now the internal combustion engine and referring to Fig. 2 it will be noted that the two cylinders 8 and 9 are secured together by bolts 25 and that the lower cylinder 9 is fixed to the upper end of the barrel 10 by means of bolts 26. The cylinders 8 and 9 are so connected that the respective explosion chambers 27 and 28 are aligned and form, in effect, a single chamber in which the driving piston 11 reciprocates. Opening into explosion chambers 27 and 28 are passageways 29 and 31 respectively, by which a compressed charge of gasoline laden air is introduced into the combustion chambers. Respective exhaust ports 32 and 33 are also provided in each combustion chamber to permit the escape of burned gases. Communicating with the passageways 29 and 31, by means of ports 34 and 35, is a pre-compression chamber 36 closed by the piston 11. A piston head 38, formed midway along the driving piston, has a sliding fit with the bore of chamber 36 and divides it into upper and lower compartments. Separate valves 39 and 41 contained in respective housings 40 and 42 are provided for controlling the flow of the explosive mixture into the passageways 29 and 31. These valves are alike and a description of the construction and operation of one will suffice for both. The valve is of the poppet type and is urged by a spring 43 into the position shown in Fig. 2 where it acts to close the valve opening 44 leading into a passageway 29 or 31. Access to atmosphere is obtained through the valve housing by means of ports 45, and gasoline is directed to the valve opening from a tank (not shown) through a passage 46 communicating with inlet 47. A set screw or metering valve 48 is provided for regulating the flow of liquid fuel through passage 46. The valves 39 and 41 have been shown in their present positions principally to simplify the disclosure. In the actual construction of the machine the valves may occupy the positions shown but a preferred arrangement is to have the valves side by side and approximately 90° from the positions shown. In the latter construction a single metering valve 48, common to both valves, may be used, although if it should be found desirable to burn a richer mixture in one chamber than the other,

the present arrangement of two metering valves may be retained.

In considering the operation of the engine it may be assumed that, in Fig. 2, the piston 11 has just been driven upward by an explosion in the lower chamber 28 and a compressed charge is trapped in the upper chamber 27 ready to be ignited by a spark from a plug 49 extending into the upper end of the chamber 27. When the explosion occurs in chamber 27 the piston 11 is driven downwardly to seal the passageway 31 and exhaust port 33, from the lower chamber 28, and, as the piston head 38 moves through the pre-compression chamber 36 it acts to compress the previously introduced charge in the lower compartment of chamber 36 and in passageway 29. A partial vacuum is thus created in the upper compartment above head 38 and atmospheric pressure upon valve 41 acts, at this time, to unseat this valve and thereby permit an explosive mixture to enter passageway 31 and proceed in the direction of the arrows in Fig. 3 into the upper pre-compression chamber 36. As the piston 11 continues to descend it uncovers first the exhaust port 32 in the upper chamber 27 and then the inlet from passageway 29. Thus at approximately the same time the burned gases escape through port 32 at one side of chamber 27 and a fresh mixture enters the chamber from its opposite side. A projection 51 is formed on each end of the piston 11 and acts as a deflector to send the fresh gas toward the end of the combustion chamber and away from the exhaust port. The movement of the gases at this time is indicated by the arrows in Fig. 5 wherein the piston is shown in its extreme downward position just prior to the ignition of the compressed charge in chamber 28 by a plug 52 extending into the lower end of this chamber. The charge now in chamber 28 was introduced therein during the previous upward stroke of the piston 11.

As the piston 11 is driven upwardly the operation described above is repeated but reversed. That is, during this stroke, the mixture previously admitted to upper chamber 36 is compressed by movement of piston head 38 and when passageway 31 is uncovered this mixture enters the chamber 28 as the burned gases escape therefrom through port 33. As the same time a partial vacuum is being created in lower chamber 36, thereby causing the poppet valve 39 to open and admit a fresh mixture into this chamber and passageway 29 which has been sealed by upward movement of the driving piston. By reason of the above arrangement, the piston 11 is given a positive reciprocating motion and the effect obtained is that of two engines operating upon a single piston with each engine functioning on the basis of two strokes for one cycle.

The ignition system used in conjunction with the engine may be energized from an outside source such as a battery 53 (Fig. 2). Individual coils C-1 and C-2 are connected to the respective spark plugs 49 and 52 and have a common connection to the negative side of the battery. The positive terminals of the coils are connected respectively to contacts 54 and 55 engageable with an armature 56 connected directly to the positive terminal of the battery. The armature 56 is in the form of a bell crank lever and is adapted to pivot about an axis 57 to engage one or the other of the contacts 54 and 55 to close the circuit through a coil C-1 or C-2 and cause a spark between the points of plug 49 or 52. A pair of oppositely disposed springs 58 and

59, connected to lever 56 above its pivot point 57, tend to centralize the lever in a position intermediate the contacts 54 and 55 to maintain the circuit through both coils normally open. The lever 56 is arranged for cooperation with a stud 61 fixed to the cylindrical cage 13, which stud may, if desired, be formed as an extension on a wrist pin 62 which passes through the upper end of the cylindrical cage 13 and the lower end of connecting rod 12 to effect a rigid connection between the cage and the driving piston 11. The stud 61 projects through a longitudinal opening 60 cut in the barrel 10. The edge of the lever 56 which engages the stud 61 is formed with separate inclined surfaces 56A and 56B which converge to a low point adjacent the pivot point 57. Thus, with the driving piston 11 in its upper position as shown in Fig. 2, the stud 61 engages the upper end of inclined surface 56A to hold the lever 56 rocked against the tension of spring 58 to close the circuit through coil C-1 to plug 49 and cause an explosion in upper chamber 27. Now, as the driving piston descends, the stud 61 moves downward along surface 56A and, as it approaches the mid-way point shown in Fig. 3, moves out of engagement with the lever and allows the spring 58 to centralize the lever and open the circuit. Continued downward movement of the piston causes the stud 61 to engage inclined surface 56B and, as the piston reaches its Fig. 5 position, the lever 56 is rocked in a clockwise direction to engage contact 55 and establish a circuit through coil C-2 to spark plug 52 and cause an explosion in lower chamber 28. Return movement of the piston will, of course, cause a counter-clockwise movement of the lever 56 resulting in another explosion in the upper chamber 27. The timing mechanism thus operates under the control of the cage 13 to cause explosions alternately in the chambers 27 and 28.

Any suitable means may be used to start the engine. One such means is shown here and comprises a manually operable plunger 63 extending downward through the upper end of the cylinder 8 and into the chamber 27. The lower end of plunger 63 is formed with a pin 63a (Fig. 7) adapted to be inserted in a bayonet slot 64 in the top surface of the upper projection 51. The plunger 63 may be locked to the piston 11 by inserting the pin 63a into the slot 64 and then twisting the plunger slightly against the force of a combined torsion and compression spring 65 which surrounds the stem of the plunger. The plunger may then be manually pumped up and down to reciprocate the driving piston and start the engine. The plunger, when released, will be twisted back to normal by the spring 65 and returned to the position shown in Fig. 3. A valve like head 66 is formed on the plunger 63, near its lower end, and is normally positioned on a seat 67 formed in the cylinder 8 to prevent leakage from the explosion chamber 27.

Referring now to Figs. 1, 4 and 6, the hammer assembly comprises, as before mentioned, the cylindrical cage 13 and the hammer piston 14 positioned within the cage and movable relatively thereto. The principle of free piston hammers is old and well known in the art and a variety of practical embodiments thereof may be produced. The patent to C. B. Coates No. 1,191,948, issued July 25, 1916, shows a hammer assembly similar to that disclosed herein. The cage 13 is formed with shoulders 68 which engage the inner surface of the barrel 10 to hold the cage against 75

lateral movement as it reciprocates with the driving piston 11. The hammer piston 14 is formed with a head fitting snugly against the inner wall of the cage, and a stem or extension 5 which passes through the lower end of the cage in position to strike the tampering bar 15. The cage 13 is closed at its upper end and sealed at its lower end by the passage of the hammer piston 14 therethrough. A slot or slots 69, slightly longer than the head of hammer piston 14, are cut in the cage at its mid point in order that the mean pressures on opposite ends of the piston head may be approximately equal to each other and to atmospheric pressure. The upper and lower ends of the cage form respective air cushions or chambers 71 and 72. As the cage descends relative to the hammer piston the air in upper chamber 71 is compressed and drives the piston 14 downward to strike the bar 15. In the upward movement of the cage relative to the hammer piston the air in lower chamber 72 is compressed and tends to return the piston to its Fig. 1 position. During the initial downward movement of the cage the piston 14 first completes its upward movement and then starts down but, due to its inertia, at a slower instantaneous speed than the cage 13. Until the speed of the piston 14 overtakes that of the cage, the size of the air pocket 71 decreases, as will be apparent from a comparison between Figs. 2 and 4. During the latter part of the downward stroke of the cage, the compressed air in pocket 71 expands, causing the hammer piston to move at a much greater speed than the cage 13. At the time the hammer piston 14 strikes the bar 15, it is moving independently of the cage 13 and the cage may start its return movement at the time of or slightly before the impact, without materially lessening the effectiveness of the blow delivered by the piston. In Fig. 6, the hammer piston has hit the bar 15 and rebounded slightly and the cage 13 is in its lowermost position.

It is possible to produce embodiments of the invention other than the one shown herein and it is intended that only such limitations shall be imposed upon the invention as are defined in the appended claim. Moreover, the illustrative embodiment is susceptible of other uses than described herein, as the hammer may be used to strike working implements other than tamper bars, for example drill steels.

What is claimed is:

An internal combustion hammer, comprising a cylinder having a combustion chamber formed at each end thereof, a hammer barrel secured to one end of said cylinder and axially aligned therewith, a working tool supported at the outer end of said hammer barrel, a driving piston reciprocable within said cylinder, a hammer assembly within said barrel including a reciprocable cylindrical cage and a floating piston therein arranged to deliver impacts to said working tool, an ignition system including a contact element adapted when set in one position to cause an explosion in one of said combustion chambers and when set in another position to cause an explosion in the other of said combustion chambers, a connection between said driving piston and said cylindrical cage, and means comprised in said connection and extending laterally through an opening in said hammer barrel into engagement with said contact element for effecting operation of said element.
